UNITED STATES PATENT OFFICE

CURT HÄNSEL, OF FORST, GERMANY

STIFFENING FABRIC FOR WEARING APPAREL

No Drawing. Application filed June 28, 1928, Serial No. 289,084, and in Germany September 5, 1927.

This invention relates to a woven fabric of the kind used as a stiffening inter-lining in the manufacture of wearing apparel. The object of the invention is to produce a fabric having durable stiffening qualities and being equally elastic in all directions, and the invention consists in interspersing the warp as well as the weft threads uniformly in equal fashion which stiffening threads in the form 10 of natural or artificial horsehair overspun in known manner with cotton, silk, linen or the like.

The number of such horsehair threads employed depends on the required stiffening effect.

The other warp and weft threads employed may be linen or woolen or composed of animal fibres of various kinds chosen with a view to obtain very fine variations in 20 the degree of flexibility.

The kind of weaving employed is immaterial. Ordinary plain cloth weave is sufficient for most purposes, but ground or other weaves may be employed if required.

25 I claim:

1. For use in wearing apparel, a stiffening interlining comprising a ground fabric of hair yarn equally stiff and elastic in warp as well as in weft, modified by a replacement of 30 threads, in equal and definite spacing in warp as well as in weft, by threads of other kinds.

2. For use in wearing apparel, a stiffening interlining comprising a ground fabric of hair yarn equally stiff and elastic in warp as 35 well as in weft, modified by a replacement of threads, in equal and definite spacing in warp as well as in weft, by stiffening threads in the form of horse-hair overspun with other material.

40 3. For use in wearing apparel, a stiffening interlining comprising a ground fabric of hair yarn equally stiff and elastic in warp as well as in weft, modified by a replacement of threads, in equal and definite spacing in warp 45 as well as in weft, by threads of less stiffness and rigidity than the hair yarn.

CURT HÄNSEL.
